United States Patent Office.

M. S. ORTON, OF GALESBURG, ILLINOIS, ASSIGNOR TO ZIMRI POND, OF SAME PLACE.

Letters Patent No. 101,304, dated March 29, 1870.

IMPROVEMENT IN PUMPS.

The Schedule referred to in these Letters Patent and making part of the same.

To all whom it may concern:

Be it known that I, M. S. ORTON, of Galesburg, in the county of Knox and State of Illinois, have invented certain new and useful Improvements in Pumps; and I do hereby declare that the following is a full, clear, and exact description of the construction and operation of the same, reference being had to the accompanying drawings making a portion of this specification, in which—

Figure 1 is a vertical central sectional view.

The nature of this invention relates to improvements in that class of pumps having a hollow piston-rod; and

The invention consists in constructing the piston with an air-chamber in its lower surface, and extending the hollow piston-rod down through the said air-chamber to near a level with the base of the piston.

To enable others to construct and use my invention, I will proceed to describe it with reference to the drawings.

Letter A represents the framing or curb of the well or cistern, to which the device is applied.

Letter B represents a cylinder, open at the top, and with a hole, S, in the bottom.

This cylinder is supported at a short distance from the bottom of the well or cistern on the braces D D.

Y represents a valve over the hole S, and opening upward.

C represents the cylindrical piston, hemispherical over the top, hollow on the under side, and fitting neatly in the cylinder B.

L represents a hollow piston-rod, curved over at the top, as shown, and forming the discharge-pipe.

H represents a lever, pivoted to the curb A by the hook J, and to the pipe L by the pin, shown by dotted lines e.

The manner of operation is deemed evident from the drawings.

When the piston C is lifted by means of the lever H, the valve Y will be raised, and the water drawn into the cylinder B, and when the piston is forced downward, the valve Y will be closed, and the water in the cylinder B forced upward and discharged from the pipe L, the air at the same time surrounding the lower end of the pipe L, in the under side of the piston, and aiding, by its elasticity, in securing easy action and regular working of the pump.

I do not claim as my invention the tubular piston-rod, nor any method by which other pumps having tubular pistons are operated by valves on their lower end. My invention obviates the necessity for valves on the piston.

What I claim as my invention is—

The air-chamber or piston C, attached to the lower end of, and in combination with, the hollow piston-rod or tube L, cylinder B, lever H, and valve Y, the whole constructed and operated substantially as and for the purpose specified.

Signed at Galesburg, in the county of Knox and State of Illinois, this 27th day of March, 1869.

M. S. ORTON.
